UNITED STATES PATENT OFFICE.

CHARLES D. WAHL, OF PHILADELPHIA, PENNSYLVANIA.

LOOM.

1,102,110.

Specification of Letters Patent. Patented June 30, 1914.

Application filed June 15, 1912. Serial No. 703,937.

To all whom it may concern:

Be it known that I, CHARLES D. WAHL, a citizen of the United States, residing at Philadelphia, in the county of Philadelphia and State of Pennsylvania, have invented new and useful Improvements in Looms, of which the following is a specification.

This invention relates to looms, and particularly to filling mechanism therefor, one object of the invention being to provide a mechanism whereby the usual multiple shuttle boxes on each side of the loom may be dispensed with and replaced by a single shuttle operable to carry any desired thread through the warp, thus simplifying the filling mechanism of the loom structure to a material degree.

A further object of the invention is to provide a mechanism which will select the proper thread, attach it to the shuttle for drawing through, and attach a second thread to the same shuttle to be drawn through on the return movement of the shuttle, the use of shuttle cops being entirely dispensed with.

A still further object of the invention is to provide thread setting elements controlled by a suitable type of automatic pattern device for coaction with the shuttle, together with suitable means on the shuttle and loom frame for picking up, clamping and severing the selected threads at predetermined periods.

The invention consists of the novel features of construction, combination and arrangement of parts hereinafter fully described and claimed, reference being had to the accompanying drawings, in which:—

Figure 1 is a plan view of the filling mechanism on one side of the loom with one filling thread in position to be carried through the warp by the shuttle. Fig. 2 is a detail view of one of the thread setting levers. Fig. 3 is a detail view of the presser-foot for retracting the setting levers. Fig. 4 is a vertical transverse section on the line 4—4 of Fig. 1, showing the cam blocks and parts of the mechanism in duplicate at each side of the machine, and also showing at each side one of the thread setting levers elevated. Fig. 5 is a plan view of a portion of the pattern strip. Fig. 6 is a plan view of the pattern cylinder. Fig. 7 is a vertical longitudinal section on the line 7—7 of Fig. 1. Fig. 8 is a vertical longitudinal section on the line

8—8 of Fig. 1. Fig. 9 is a view similar to Fig. 7 but with the parts in a different position at another stage of operation. Fig. 10 is a detail view of the reciprocating controller bar. Fig. 11 is a vertical transverse section on the line 11—11 of Fig. 9. Fig. 12 is a plan view of the shuttle with the thread clamping and cutting mechanism thereon in normal position. Fig. 13 is a vertical longitudinal section on the line 13—13 of Fig. 12. Fig. 14 is a vertical transverse section on line 14—14 of Fig. 12, showing the devices thereon about to sever and clamp the thread. Fig. 15 is a similar view showing the thread clamped. Fig. 16 is a face view of the cam block on the right side of the machine. Fig. 17 is a side elevation of the same.

In practice, the filling mechanism is duplicated at each side of the machine. I have, however, only deemed it necessary to show in full the filling mechanism at one side of the machine, as the operation of the filling mechanism at the opposite side will be readily understood from the subjoined description.

Referring to the drawings, 1 designates the breast-beam of the loom-frame, 2 the vibrating lay, and 3 the reed section, all of which may be of any ordinary or well known construction. 4 denotes the shuttle which is mounted to travel in the usual raceway and may be actuated by any ordinary or suitable type of operating means.

In accordance with my invention, the shuttle is provided at each end with a chamber or cavity 5 containing sets of thread severing, clamping and releasing devices, respectively arranged for operation on the reverse directions of travel of the shuttle. Each of these sets of devices comprises a stationary cutting blade 6, a coacting movable cutting blade 7, and a clamping blade or finger 8, arranged opposite the blade 6. The blade 7 is pivoted at one end, as at 9, for vertical movement, and its free end 10 is adapted to be forced down between the blade 7 and finger 8 to sever the picked-up filling thread and clamp it for travel through the warp. The said free end of the blade 7 normally projects upwardly from the cavity 5 and is adapted to be depressed on its cutting and clamping motion by a cam device, herein-after described. Pivotedly mounted for ver-

tical motion on a cross rod 11 is a releasing or trip lever 12, pivotally connected at its lower end by a crank arm 13 to the blade 7 and having a curved free end 14. The blade 5 7 and lever 12 are thus connected to move simultaneously in opposite directions, so that when the free end of the blade is projected the free end of the lever will be depressed, and vice versa. The function of 10 this lever is to retract the blade 7 at the limit of travel of the filling thread and thus release the latter. The blade or finger 8 is backed by a pressure spring 15.

Secured to the side of the loom frame is a 15 supporting beam 16 carrying contacts 17 and 18, and mounted to slide or reciprocate longitudinally on said beam is an actuating bar or rod 19 provided at one end with a contact pin or projection 20 and at its opposite end with a contact arm or projection 21, which latter lies in the path of backward motion of the vibrating lay 2. The said bar or rod 19 is further provided with a contact pin or projection 22. In the present instance, the bar is shown as provided with 25 longitudinal slots 23 engaging suitable projections 24 from the beam 16, whereby said bar is reciprocably mounted. Movable with the lay is a block 25 having oppositely disposed inclined or cam faces 26 and 27, arranged respectively in the lines of travel of the end 10 of the blade 7 of one set of thread cutting, clamping and releasing devices, and the end 14 of the releasing lever 12, of the 30 other set of thread cutting, clamping and releasing devices at the opposite ends of shuttle on the reverse motions of the latter, as hereinafter fully explained. The cam block also carries a brush or wiper 28, which 35 lies in the path of the upper surface of the shuttle, and is designed to sweep the same free of particles of thread and lint and to assist in alining the filling thread while it is being carried across the warp and while it is 40 being beaten in position by the reeds after having been released from the shuttle clamp.

Supported by the block 25 is a thread pick-up, clamping and severing device comprising a stationary clamping member or 45 blade 29 and a pivoted clamping member or blade 30, the free ends of which blades are adapted for engagement within a spring guide strip 31 to insure proper movement of the movable clamping member and engagement of the filling thread. The member 30 is of bell crank form and is provided with an upwardly projecting contact arm 32 adapted to engage the contact 17 on the backward movement of the lay to move said member into open or retracted position and to engage the contact 18 on the forward movement of the lay to close or project said movable clamping member. The downward or retractive movement of the member 30 55 is limited by a stop pin 33.

The filling threads 34 are carried by cops or bobbins 35 suitably supported at the side of the loom, and between said cops or bobbins and the woven portion 36 of the fabric said threads pass through guide openings or 60 eyes 37 in a series of setting levers 38, one for each thread. These levers extend longitudinally in parallel relation to each other and to the beam 16 and are provided with right angularly bent inner ends 39 in which 65 the eyes or guide openings 37 are formed, whereby the filling threads are normally maintained at one side of and out of the path of travel of the shuttle. The opposite ends 40 of the levers are bent upwardly at 70 an angle, and said levers are pivotally mounted at the points of junction of their body portions and arms 40 for independent 75 pivotal movement in a vertical plane on a supporting rod 41, the longer arms or body portions of the levers being normally depressed at an angle so that the threads normally lie, below and at one side of the plane of travel of the shuttle and also below the normal plane of travel of the clamping member 80 30 of the pick-up device on the cam block 25. The arms 40 of the levers are provided with depending pins or projections 42, which normally ride in contact with an endless pattern strip 43 movable over suitable 85 guide pulleys 44 and around a pattern drum or cylinder 45. Each setting lever is normally balanced by a coiled spring 46 terminally fastened to its arm 40 and an adjacent portion of the frame, which spring tends to 90 draw the pin or projection 42 down into engagement with the pattern strip and cylinder, and a similar spring 47 engages the rod 41 and contact pin or projection 22 of the 95 actuating bar 19 and serves to hold said bar normally retracted and to move it in a direction opposite to that in which it is moved by the backward motion of the lay 2.

The pattern strip 43 is provided with marginal openings 48 for engagement with 100 teeth 49 on the pattern cylinder, whereby said strip is operated by the cylinder, and the strip is also provided with pattern perforations 50 adapted to register with sockets 51 in the cylinder, a row of the perforations 50 and coacting set or series of sockets 51 being provided for coöperation with each setting lever. The cylinder is also provided with ratchet teeth 52 adapted to be engaged by the pivoted tooth 53 of a spring retracted 105 ratchet dog or pawl 54 limited in its rearward motion by a stop pin 55, which dog is adapted to be engaged and moved forward by the pin or projection 20 to transmit motion to the cylinder and pattern strip when 110 the bar 19 is moved forward by the lay 2 on the backward motion of the latter. When the lay 2 moves forward, its pressure on the arm 21 of the bar 19 is released and said bar is drawn backward by the action of the 115 120 125 130

spring 47, and at the same time the dog 54 is returned to normal position, its pivoted tooth 53 riding backward over the inclined faces of the ratchet teeth 52.

5 The perforations in the pattern sheet and coöperating sockets in the pattern cylinder are so arranged as to effect the elevation of but a single thread-elevating or selecting lever at a time. For the purpose of depressing each lever after elevation and actuation of the shuttle on its thread feeding movement, a presser foot or depressing device 56 is provided. This presser foot or depressing device is hinged at one end to the rod 15 41 and has a lateral arm 57 arranged to extend above and rest upon any of the levers, and an offset or cam portion 58 which is adapted to be engaged by the pin 22 on the inward or forward movement of the bar or 20 rod 19 to force said presser foot downward and consequently depress the lever 38 which has been elevated. In this forward movement of the bar 19 the pattern cylinder is fed up a distance of one tooth by the action 25 of the ratchet mechanism, and on the reverse or backward travel of the bar 19 the pin 22 moves out of engagement with the presser foot to release the same and the thread selecting levers to permit the next 30 lever in the cycle of operation to be elevated when the coacting perforation in the pattern sheet and socket in the pattern cylinder come into operative position. At proper periods the series of thread selecting levers at one 35 side of the machine are all depressed and maintained in depressed condition while one or the other of the set of thread selecting levers at the opposite side of the machine is in action, the pattern devices at the opposite 40 side of the machine alternating in action to control the levers of the respective sets for the feed of filling threads from the opposite sides of the machine through the warp on each back and forth travel of the 45 shuttle. In order to enable this operation to be secured, it will, of course, be understood that the mechanism described is arranged in duplicate at each side of the machine and the pattern cylinder of each set 50 of devices is provided with ratchet teeth double in number to the pattern perforations and sockets in the sheet and cylinder, so that each alternate tooth of the series will be out of register with and arranged on 55 line between consecutive selective perforations and sockets. This requires each pattern cylinder to be fed up a distance of two teeth for each lever raising operation, and between such lever raising operations the 60 projections 42 of each set of levers ride upon the surface of the coacting pattern sheet and remain depressed, while the bar 19 is moved forward by the lay between intervals of actuation of the levers. During this interval 65 of rest or inaction of the levers at one

side of the machine, one of the levers at the opposite side of the machine is projected upward to raise a thread at that side to be engaged and carried by the shuttle through the warp. The mechanism is thus adapted 70 to supply to the shuttle a thread of a selected character on each back and forth movement thereof, so that threads from the opposite sides of the machine will be alternately and consecutively carried through the 75 warp. In order to prevent lateral play of each set of thread selecting levers 38, said levers are arranged to move between suitable guide members 59 carried by a bracket 80 60 secured to the beam 16. The thread clamping device on each cam block is designed in practice to permit the thread when released from the shuttle to reel slightly from its spool, so as to give it a small and desirable amount of slack after it has been 85 pulled through the warp.

It will be understood from the foregoing description that when one of the perforations in the pattern strip register with the projection 42 of one of the levers 38, said projection will pass from said perforation into the socket 51 in the cylinder registering therewith, thus elevating the free end of the lever and lifting the thread carried thereby, which extends from the cop to the selvage 95 end of the fabric, into the path of the pick-up device on the coöperating cam block, so that in the forward movement of the lay the contact 18 will engage the arm 32 and actuate the clamping member 30 to engage and 100 sever the woven-end of the thread connected with the fabric, which drops down as a selvage end, while holding the filler end of the thread leading from the bobbin or cop clamp in elevated position, as shown in Fig. 1. 105 The thread from the bobbin thus elevated is thereby brought across the raceway and into the path of travel of the free end 10 of the clamping member 7, between which and the clamping member 6 the thread passes on 110 the motion of the shuttle across the loom. When said free end 10 of the member 7 comes into contact with the cam surface 26 of the adjacent cam block, said member is depressed, thereby severing the end of the 115 thread connected with the cam 29—30 and clamping the end of the thread leading from the bobbin, as shown in Figs. 14 and 15, for travel through the warp. After the thread has been drawn through the warp, the free 120 end 14 of the acting lever 12, which has been projected by the severing and clamping operation, above described, comes into engagement with the cam surface 27 of the cam block at the opposite side of the machine 125 and is depressed, resulting in the release of the thread, which is beaten into the fabric on the subsequent forward movement of the lay. The shuttle is now ready for backward travel across the machine, and in a similar 130

manner takes up an elevated thread at such side and carries it through the warp back to the side of the machine first mentioned, the surface 27 of the cam block at which 5 side actuates the releasing lever of the set of cutting severing and clamping devices at the opposite end of the shuttle from that first named to effect the release of the thread.

It should be said that on the forward 10 movement of the lay the contact 21 of the bar 19 is released, thereby allowing the bar to be drawn rearwardly by the spring 47 and the dog 54 to be freed for a feed-up motion by the pin 20, while at the same time the 15 projection 22, which normally engages the cam surface 58 of the pressure foot 56 to hold the levers 38 depressed, is moved backwardly out of engagement with said cam surface, allowing the pressure foot to be re- 20 tracted and the selected lever 38 to be raised. In this operation the arm 32 of the clamping member 30 also comes into engagement with the contact 18 and is closed to engage the thread in the manner before described.

25 On its backward motion, the lay engages the contact 21 and moves the rod 19 backward against the resistance of the spring 47, thus causing the contact 20 to engage and move the dog 54 on its feed-up motion, 30 while the contact 22 again engages the cam surface 58 of the pressure foot 56 to force the same down and hold the levers 38 depressed, and the arm 32 of the clamping member 30 is brought into engagement with 35 the contact 17 to open said clamping member to free the particle of thread previously taken up and clamped thereby and to reset said clamping member for the subsequent pick. It will accordingly be apparent that

40 on each forward motion of the lay the portion of the elevated and selected thread extending from the woven fabric to the bobbin will be engaged and clamped by the clamping member 29-30, which will sever the 45 fabric end of the thread from the bobbin end of the thread, on the backward movement of the lay, will carry the latter named end of the thread across the raceway into the path of the shuttle. It will further be

50 apparent that in the travel of the shuttle the acting clamp 6-7 thereon will engage the portion of the thread extending between the bobbin and the clamp 29-30, will sever that portion of the thread held by the clamp 55 29-30, while holding that portion of the thread leading from the bobbin and carry the latter named end of the thread across the loom, so that when such portion of the thread is beaten into the fabric, the conditions originally described will be restored

60 ready for a repetition of the stated operation, that is a portion of the thread will extend from the fabric to the bobbin ready to be elevated, engaged by the clamp 29-30 65 and drawn into the path of the shuttle, en-

gaged and severed from the particle of thread held by the said clamp 29-30 and carried across the loom, thereby providing for a continuous operation of the filling mechanism in a manner readily understood.

70 In each of its back and forth travels, the shuttle comes in contact with the brushes carried by the cam blocks, which brushes assist in maintaining the threads in alignment and also sweep the exposed portions 75 of the shuttle free of all lint or severed particles of thread. The filling mechanisms at the opposite sides of the machine actuate in alternation, as described, to control the setting levers and pick-up devices of the 80 respective sets, whereby on each back and forth travel of the shuttle a positive and reliable feeding action of the selected threads through the warp from opposite sides of the machine in alternation will be secured. It 85 will be understood that in these operations two pattern sheets and cylinders will be employed, but that by mounting both pattern cylinders on a common transverse shaft it will only be necessary to use a single 90 ratchet feed mechanism and single coacting actuating bar 19.

95 It will be obvious that my invention dispenses with the use of the ordinary multiple shuttle boxes on opposite sides of the loom, and substitutes therefor a single shuttle which operates to carry the threads from the opposite sides of the machine through the warp, thus dispensing with complex shuttle box mechanism and the use of a plurality of 100 shuttles having bobbins or cops, the advantages of which will be apparent to those versed in the art. By means of my improved filling mechanism filling threads selected in accordance with any prescribed 105 pattern will be positively engaged and carried through the warp, insuring reliability and certainty of operation at all speeds, and dispensing with the use of devices liable to frequently get out of order or to impair 110 the efficiency of action of the loom.

I claim:-

115 1. In a filling mechanism for looms, the combination of a series of cops, a coacting series of thread guiding devices through which the threads extend between the cops and the selvage of the fabric, means for selectively adjusting said guide devices from a normally inoperative to an operative position, a lay-controlled device for picking up a selected thread, drawing it across the raceway, and severing and clamping the thread at a point between the guiding devices and woven fabric, means controlled by the lay for regulating the action of said 120 thread clamping and severing device, a shuttle provided with a clamping and severing device to engage the thread between the first-named thread and clamping device and selected guiding device, sever the thread, 125 130

clamp the portion of the thread connected with the cop and carry said thread through the warp and finally release the same, and means for controlling said clamping and severing device on the shuttle.

2. In a filling mechanism for looms, the combination of a series of cops, a series of thread guiding devices through which the threads extend from the cops to the selvage of the woven fabric, pattern mechanism for selectively adjusting said thread guiding device from an inoperative to an operative position, mechanism for intermittently operating said pattern mechanism, a thread clamping and severing device on the lay operative on the forward motion of the lay to engage and clamp the selected thread and sever and hold the same on the backward motion of the lay to draw the clamp thread from the cop and through the guiding device across the raceway, means controlled by the lay on its backward movement to throw said severing and clamping device into action, to free the guiding device for adjustment and to activate the pattern operating mechanism, and operative on the forward motion of the lay to release the thread clamping and severing device, hold the guiding device inoperative and reset the pattern operating mechanism for subsequent action, a shuttle provided with a thread clamping and severing device operative to engage the thread held by the first-named clamping and severing device, to sever the thread between the same and the guiding device and clamp and carry the portion of the thread connected with the cop through the warp and finally release the same, and means for controlling the said thread clamping and severing device on the shuttle.

3. In a filling mechanism for looms, the combination of a series of cops, a series of thread guiding devices through which the threads pass between the cops and the woven fabric, said guiding device being pivotally mounted for vertical motion, a pattern mechanism for controlling said guiding devices, and intermittent feed mechanism for operating said pattern mechanism, a pressure foot for holding the guiding device from motion during periods of rest, a thread clamping and severing device on the lay operative on the forward movement of the lay to sever the thread between the fabric and selected guiding device, and clamp the portion of the thread leading from the cop and on the backward motion of the lay to draw said thread across the raceway and release the same after being taken up by the shuttle, lay-operated means for controlling the pressure foot, pattern operating mechanism and said thread clamping and severing device, a shuttle provided with a thread clamping and severing device operated to engage the thread held by the first-named clamping

and severing device to sever the thread, clamp the portion of the thread leading from the cop, carry the same through the warp and finally release the thread, and means for controlling the said clamping and severing device on the shuttle.

4. In a filling mechanism for looms, the combination of a series of thread guiding devices, pattern mechanism for independently and selectively adjusting the same from a normally inoperative to a working position, ratchet mechanism for actuating said pattern mechanism, a reciprocating element actuated by the loom mechanism for periodically operating said ratchet mechanism, a thread clamping and severing device actuated by the lay mechanism, said device being operative to engage the thread presented by an adjusted guiding device, dispose the same in feeding position and release the same after a predetermined period, a shuttle provided with a thread clamping and severing device operative to engage and sever the fed-up thread from the selvage and carry the thread from the cop through the warp, and means for controlling said thread clamping and severing device on the shuttle.

5. In a filling mechanism for looms, the combination of a series of thread guiding devices, loom actuated selective mechanism for independently adjusting said guiding devices from a normally inoperative to a working position, a thread clamping and severing device actuated by the lay mechanism, said device being operative to engage the thread presented by an adjusted guiding device, dispose the same in feeding position and release the same after a predetermined period, a shuttle provided with a thread clamping and severing device operative to engage the fed up thread and sever the same from the selvage and carry the thread from the cop through the warp, and means for controlling said thread clamping and severing device on the shuttle.

6. In a filling mechanism for looms, the combination of a series of thread guiding devices, loom operated mechanism for independently and selectively adjusting said devices from a normally inoperative to a working position, a thread clamping and severing device movable with the lay and operative to engage and release the thread presented by any of the adjusted guiding devices, means operative on the forward motion of the lay to actuate said clamping and severing device to engage the thread and draw it on the reverse movement of the lay to feeding position, a shuttle operative to engage, cut and clamp the fed up thread and carry the same through the warp, and means operative on the backward motion of the lay to actuate said clamping and severing device to release the thread and set said device for the ensuing clamping and severing ac 130

tion, a thread clamping and severing device on the shuttle, and means for controlling the same.

7. In a filling mechanism for looms, the combination of a series of pivotally mounted thread guiding devices, a pattern mechanism actuated by the loom mechanism for independently and selectively adjusting any of said thread guiding devices from a normally 10 inoperative to an operative position, automatic means for retracting the respective thread guiding devices after actuation, a thread clamping and severing device actuated by the lay mechanism, said device being operative to engage the thread extending between the selvage and an adjusted 15 guiding device, disposed the same in feeding position and sever and release the thread after a predetermined period, a shuttle provided with a thread clamping and severing device operative to engage the fed-up thread and sever the same between the selvage and the aforesaid clamping and severing device and clamp and carry the thread from the 20 cop through the warp, and means for controlling said thread clamping and severing device on the shuttle.

8. In a filling mechanism for looms, the combination of a series of thread guiding devices, selective mechanism for adjusting any of said guiding devices from a normally 25 inoperative to a working position, means for engaging and disposing in feeding position

and finally severing a thread presented by any of the selectively adjusted guiding devices and releasing said thread after a predetermined period, a shuttle provided with means for severing the fed up thread and gripping the free end of the thread and carrying the same through the warp, and means for releasing the thread and resetting said severing and gripping means at the limit of motion of the shuttle.

9. In a filling mechanism for looms, the combination of a series of thread guiding devices, pattern mechanism for selectively adjusting said guiding devices from a normally inoperative to a working position, means for engaging and disposing in feeding position a thread presented by any of the selectively adjusted guiding devices, a shuttle provided with a fixed and pivoted member adapted to sever the thread and grip the free end thereof to carry said thread through the loom, and also provided with a releasing device for freeing the thread and returning said members to normal position, and means on the loom structure for controlling said thread severing and gripping members and said releasing device.

In testimony whereof I affix my signature in presence of two witnesses.

CHARLES D. WAHL.
